UNITED STATES PATENT OFFICE

160,051

TIE HOLDER

Olof V. Anderson, Cowesett, R. I., assignor to Anson Incorporated, a corporation of Rhode Island

Application January 13, 1950, Serial No. 7,200

Term of patent 14 years

(Cl. D17—10)

To all whom it may concern:

Be it known that I, Olof V. Anderson, a citizen of the United States, residing at Cowesett, in the county of Kent and State of Rhode Island, have invented a new, original, and ornamental Design for a Tie Holder, of which the following is a specification, reference being had to the accompanying drawing, constituting a part hereof.

Fig. 1 is a front view of a tie holder, showing my new design; and

Fig. 2 is a side view thereof.

I claim:

The ornamental design for a tie holder, substantially as shown.

OLOF V. ANDERSON.
